UNITED STATES PATENT OFFICE.

JOHN A. THOMPSON, OF SEATTLE, WASHINGTON.

DESIGN FOR A TWINE-HOLDER.

SPECIFICATION forming part of Design No. 32,475, dated April 10, 1900.

Application filed February 2, 1900. Serial No. 3,753. Term of patent 7 years.

To all whom it may concern:

Be it known that I, JOHN A. THOMPSON, a citizen of the United States, and a resident of Seattle, in the county of King and State 5 of Washington, have invented and produced a new and original Design for a Twine-Holder, of which the following is a specification.

Reference is to be had to the accompanying drawings, forming a part of this specification, 10 in which similar characters of reference indicate corresponding parts in both the views.

Figure 1 is a perspective view of a twine-holder, showing my design; and Fig. 2 is an enlarged plan view of the same.

15 The design in its entirety consists of a base A, from the middle of which rises a truncated cone B, whose sides are continuously tapered, as shown, and from the ends of the base A extends upward a frame having side rods C 20 C', slightly inclined inwardly toward each other and connected with each other at their upper ends by a cross-bar D, having an eye E at or near the middle, an eye F at the junction of the rod C with the cross-bar D, and a 25 corrugated bar G, depending from the cross-bar between the eyes E and F, the eye F

standing transversely and approximately at a right angle to the eye E, as plainly indicated in Fig. 2, the end of the base A at the lower end of the rod C appearing with an eye-opening I.

The leading feature of my design consists of the base A, the regularly or continuously tapered truncated cone B, and the frame, in whose cross-bar D appears a middle eye E, a 35 corner-eye F, standing at right angles to the eye E, and a corrugated bar between the two eyes and whose corrugations appear entirely below the cross-bar D.

Having thus fully described my invention, 40 I claim as new and desire to secure by Letters Patent—

The design for a twine-holder, as herein shown and described.

In testimony whereof I have signed my 45 name to this specification in the presence of two subscribing witnesses.

JOHN A. THOMPSON.
